APPARATUS FOR REDUCING ORES AND
MELTING METALS BY ELECTROMAGNET-
IC INDUCTION

Clarence Q. Payne, New York, N. Y.

Application December 2, 1942, Serial No. 467,608

4 Claims. (Cl. 13—26)

This invention relates partly to improvements in my Patent No. 2,281,170 and partly to new features whereby the field of usefulness of the induction furnace can be greatly extended. It is adapted to the treatment of all ores which are electrically conductive or magnetically permeable, and which can, therefore, be internally heated by means of alternating electric current. The invention is especially available for the treatment of finely divided ores, such as flotation concentrates, or ores which require fine crushing to unlock them from their gangue minerals. For such material close temperature control is desirable and is herein provided by means of rheostat control of the current in the primary coil, in order to adapt it to a variety of ores.

This invention consists essentially in so combining an alternating current electromagnet with an induction furnace that the charge of the latter forms the central core of the electromagnet. It also comprises so shaping the charge that its lower portion diminishes in volume whereby, with a reducing agent, it may be progressively reduced, at a low temperature and continuously discharged from the bottom of the furnace while the upper portion is absorbing heat by contact radiation from the lower portion, as well as from electromagnetic induction within the charge itself. The same type of furnace may also be used at a higher temperature for melting a reduced product like sponge iron, to pure ingot iron.

Instead of providing an electromagnet as shown in my Patent No. 2,281,170 with a single magnetic flux circuit, and then causing a strong flux condensation at the coned end of the crucible charge, I find it advantageous to provide the electromagnet with a dual flux circuit and to give each a strong magnetic "edge" condensation at the restricted flat bottom of the charge. The rapid reversals of these flux condensations by the alternating current greatly assist in heating the charge.

An important and novel feature of my present invention is to cause the charge to move downward by its own weight as it passes through a refractory regulating discharge-gate at the bottom of the furnace. This enables the operation of the furnace to be continuous. In order to assist free movement of the fine particles of the charge among themselves, and to avoid their sticking to the furnace walls the entire furnace is given an active vibration. The electromagnet is provided both with a primary and also with a secondary coil. These coils are of the so-called

"shell" type of windings; that is, they are concentric with each other and the magnetic flux circuit is on the outside of the windings. The secondary coil is given a "load circuit" by causing its terminals to close through the furnace charge.

The nature of the invention will be better understood from a description of the accompanying drawings, which form part hereof and in which:

10 Figures 1 and 2 show in side and end views the furnace assembled on a table support, with a motor and an out-of-balance flywheel to impart a rapid vibrating motion to the ore charge while it is undergoing reduction or melting.

15 Figure 3 shows in vertical cross-section the electromagnet so combined with an induction furnace that the core of the electromagnet forms the charge of the furnace.

20 Figure 4 shows in sectional view along the plane 4—4 of Figure 3 the magnetic "edge" concentrations of the lines of force in the dual flux circuits at the bottom of the furnace charge.

25 Figure 5 shows in sectional view on the line 5—5 of Figure 3 the refractory sliding gate which controls the discharge of the reduced product from the furnace.

Figure 6 shows a top view of the gate along the line 6—6 of Figure 5.

30 As heretofore designed practically all induction furnaces are provided with an iron core in which the magnetic flux is generated by the electric current in its primary winding. The magnetic flux is then transformed by induction into a high amperage current in the secondary coil (which consists of the ore charge, or metal, surrounding the core) and is converted into heat by the magnetic reluctance of the latter. This design involves certain disadvantages which increase with the size of the furnace. Here the distances which separate the primary and the secondary coils cause considerable magnetic leakage and this involves a high power loss.

35 In my present induction furnace, on the other hand, I utilize part of the ore charge (which is given a tapering shape as shown in Figure 3) as the core of the electromagnet in which to generate the magnetic flux. The ore charge, which is given a downward movement through the furnace by its own weight, will have a considerably greater magnetic reluctance than that of an iron core, due to the lower permeability of its material and to the finely divided state of its particles. This reluctance shows itself in greater hysteresis losses and in eddy currents than would be the case in an iron core, and these rapidly develop

a high temperature in the charge. This design thus secures part of the furnace heat directly instead of wholly by transformation. The remainder of the path of the dual flux circuit, outside the core, as shown at 13, 14, 15 and 16 in Figure 3 is carried by laminated transformer iron which has a high magnetic permeability and low magnetic reluctance. Their dimensions are also made ample in order to avoid any appreciable temperature rise due to the flux reversals of the current which they carry. There remain only the small air-gaps in the flux circuit shown at top and bottom of the crucible furnace in Figure 3. The entire length of the circuits as shown in Figure 3 is approximately as follows:

	Per cent
Two divided iron paths, each	61.0
One central core	30.0
Two divided air-gaps, each	9.0
	100.0

It will be evident from the above that the magnetic permeable portion of each flux circuit amounts to 91.0% of the whole. Only enough air-gaps have been provided in these flux circuits to enable the crucible to be removed for repairs and replaced at such intervals when it may become necessary. In this way the magnetic leakage is quite small and the power factor and efficiency of reduction should therefore be quite high.

Since the ores and minerals to be treated in this furnace will vary widely in their magnetic permeability, and since some of them lose their magnetism at high temperatures, there is provided as a safeguard in reaching a sufficiently high temperature in the core, a secondary coil as shown at 12 in Figures 3 and 4. This consists of a few turns of copper tubing insulated with asbestos tape on the outside and water cooled on the inside. This secondary coil encircles the lower part of the crucible. It serves to transform or "step up" the amperage of the primary coil. This gives it great heating value. Moreover, to provide a suitable load in this circuit, the terminals of the secondary coil are made to close through the lower part of the charge as shown at A-B in Figure 3. This assures an ample heat range to reduce or to melt the lower part of the charge viz.: from 700° C. to 1500° C. under close rheostat control. The upper part of the charge, where its volume expands, undergoes only partial reduction. As it gradually descends through the crucible its volume is reduced until it reaches the highest temperature zone of reduction or melting. The crucible is open at its lower end and rests in a refractory support 30, Figure 3, which is held to the lower yoke of the electromagnet. This support contains a small supply of the reduced material and below it a regulating, or control, gate which maintains the charge in motion at a desired rate of discharge of the finished product, by varying the amount of the opening, as shown in Figures 5 and 6.

The object of this invention is not only to reduce iron ores, especially their oxides, with a reducing agent to sponge iron at a low temperature, but also to melt the reduced sponge iron in the same type of furnace to the metallic state at higher temperatures to pure ingot iron. This latter operation is accomplished preferably after the non-metallic or gangue particles of the ore have been removed from the reduced sponge iron.

The preliminary reduction of iron ores at a low temperature, 900° C., to a pure sponge iron is a somewhat more difficult matter than melting the sponge iron. A reducing agent is then required and must be added in order to get rid of the oxygen, etc., of these ores. This should be done so that the least amount of impurity is added in order not to affect the value of the sponge iron when used thereafter for high grade steel alloys.

Hydrogen is undoubtedly the purest of the various reducing gases and does not introduce any impurities in the reduced sponge iron. While this gas may be applied under pressure to my furnace by providing suitable openings in the lower part of the crucible 10, yet there are certain difficulties, or objections, to the use of gas for this purpose. In the first place, it is more expensive for the same amount of reduction than a solid reducing agent like carbon, in the form of coke, coal, or charcoal. It also involves in this case greater difficulty in the accurate adjustment of the right amount of gas for the efficient reduction of the countercurrent moving column of ore. By overcoming the difficulties, which have been associated with the use of carbon in the reduction of iron ores in other reducing furnaces, it is possible to utilize carbon for low temperature reduction of iron ore to sponge iron in my induction furnace and to thus attain a notable economy in the operation of the furnace.

In order to illustrate the great reducing power of carbon, we may take a hematite ore which we will assume contains 55% metallic iron. When raised to the temperature of reaction, the equilibrium equation is then as follows:

From this it is seen that a long ton (2240 lbs.) of hematite ore containing 55% iron, will require only 198 lbs. of carbon

$$\left(\frac{36}{224} \times 1232 = 198 \right)$$

to reduce the 1232 lbs. of metallic iron which is present in the ton of crude ore. Since the carbon may be derived from coke or coal, which usually contain about 90% carbon, the reduction will actually require 220 lbs. of coal for the complete reduction. With coal at \$5.00 per (short) ton this will represent a fuel cost of only 0.55 cent per ton of the 55% hematite ore. The heat derived from this small amount of carbon is required only for the chemical reaction of the reduction. A certain amount of additional heat is also required to start the reaction and to control the temperature. This is obtained by electromagnetic induction from the electromagnet as shown in Figure 3. This internal heat reacts only with the ore particles and not at all with the gangue particles nor with the coke or coal of the furnace charge.

Care should be taken in the use of carbon in my furnace for the reduction of the iron oxides (instead of hydrogen) to prevent temperature rises higher than 900° C. It is, however, quite important to maintain the average temperature of the reduction at about 900° C. in order to prevent sintering of the ore particles, and introducing impurities into the sponge iron produced. This can be done by the following steps.

1. When the amount of carbon used is limited to that needed for the actual reduction of an iron ore, as in the case of the 55% hematite men-

tioned above, only 10% of coal or carbon is required. This is crushed to about the same degree of fineness as the ore particles themselves and is intimately mixed with them.

2. The iron ore reduction is an endothermic reaction and absorbs considerable heat. Since the ore and its gangue comprise 90% of the charge, the coal particles are widely separated; the preponderating ore particles will tend to reduce the temperature more than the coal particles will tend to increase it above the 900° C. limit desired. It is, therefore, necessary to supply an outside source of heat to maintain the right heat level. This is derived from electric induction heat as here explained.

3. The heat thus availed of is internal heat and acts only on the ore particles and not on the gangue particles in the ore. It also acts from within outward, and the amount of heat supplied is under close rheostat control, as shown in Figure 3. The absorption of carbon when in contact with coarse iron particles forms iron carbide quite slowly. In my furnace the small size of the ore particles, their intimate mixture with the coal particles, and their rapid vibration cause the reduction to proceed through innumerable contact points and through the gas phase very rapidly. In this way it is possible to keep the carbon limit in the sponge iron down to 0.10% to 0.20% and thus make it available for high quality steel alloys, as well as for other uses.

The operation of the furnace will be quite clear from the above description of the principle on which it is designed. From Figures 1 and 2 it will be seen that the base of the induction furnace is mounted on an angle-iron frame 17, 18, provided with an end extension which supports vertically adjustable bearings and a shaft. These carry the flywheel 20. The flywheel is driven by a belt from the motor 21, placed directly below it. Adjustable weights placed close to the rim of the flywheel enable it to be thrown out of balance and thus to develop a variable amount of centrifugal force. The frame 17, 18 and the furnace attached to it are supported on rollers 19 which rest on the table top 22. When the motor is in operation it revolves the flywheel at a speed of about 1800 R. P. M. and the centrifugal force of the flywheel imparts a minute but very intense oscillation, or vibration, to the frame and through it to the ore particles in the crucible of the furnace, without any direct mechanical connection between the motor and crucible. This active vibration of the ore particles greatly assists in the reduction of the ore to sponge iron by constantly presenting new points of contact between the ore and coal particles, as they move actively among themselves, and in the steady downward movement of the charge through the crucible. It also assists the CO₂ gases to move upward while the reduced sponge iron moves downward, and tends to prevent sticking of the heated particles to the crucible walls. It thus increases the capacity of the furnace by reducing the time required for reducing the ore to sponge iron.

The heat required for equalizing and maintaining the ore charge at a temperature of about 900° C. is obtained from alternating electric current by induction from the primary 11 and secondary field coil 12, which are placed concentrically around the ore charge in the crucible 10, of Figure 3. The electromagnet is preferably designed with a dual magnetic flux circuit as shown by the broken lines in Figure 3. Each of these flux circuits is given an intense edge con-

centration of the magnetic flux, as shown in Figure 3, and diagrammatically in plan view in Figure 4 at 102. These assist in creating an intense local heating zone at the bottom of the crucible, as the charge moves progressively through it. As a further safeguard in securing a high limit of temperature, for melting certain reduced ores, I also make use of a load circuit of the induced current from the secondary coil by causing the terminals of the secondary coil to be closed by the lower part of the charge in the crucible as shown at A—B in Figure 3, where the added heating effect will be most effective.

The lower end of the crucible 10 is open and rests upon a highly refractory support 30 which contains a horizontal sliding gate which is operated by a shaft 32 and hand wheel 33, Figure 2. The opening and closing of the gate, on which the rate of discharge depends is controlled by a suitable screw on the shaft 32, which is revolved in the fixed bearing 34.

When the reduced ore, as sponge iron, is discharged from the furnace it is made to fall upon inclined water cooled plates 40, 41, in order to chill it quickly and to prevent reoxidation. These plates are attached by flanged cheek-plates to the bottom of the furnace frame 17, 18, and vibrate with it. They, therefore convey it downward until the sponge iron falls into the receptacle 42. This cooled sponge iron is then put through separators to remove the nonferrous material from the sponge iron concentrate, and is then utilized for the various purposes to which it is adapted. If it is desired to melt the sponge iron to ingot iron, the cooling plates 40, 41 are omitted and the temperature of the furnace is raised to about 1500° C. The molten sponge iron as it is discharged from the furnace is then allowed to fall into ingot molds and to cool very slowly so that it will retain its low carbon softness, which makes it very desirable for varied steel alloy use.

This furnace although designed primarily for the reduction and melting of iron ores, may also be utilized for certain nonferrous ores either for reduction or melting. The above description is therefore merely illustrative and it is understood that modifications may be made without departing from the spirit of the invention as defined in the appended claims.

I claim:

1. Apparatus for reducing finely divided iron ores which includes a vertical alternating current electromagnet having a dual magnetic flux circuit and an induction furnace whose charge forms the continuously downward moving core of the electromagnet; means for raising the lower end of said core-charge to a higher temperature than its upper end; means for vibrating said charge, in combination with means for continuously removing the reduced material from the bottom of the furnace through a refractory regulating gate.

2. Apparatus for reducing finely divided iron ores which comprises the combination of a vertical alternating current electromagnet and an induction furnace whose moving charge forms the central core of the electromagnet; means for transforming the amperage of the flux circuit of the primary coil into a higher amperage in that of the secondary coil, and means for utilizing the heat of the load circuit developed by induction in the secondary coil by closing the terminals of the secondary coil through the ore charge.

3. In a low temperature induction furnace for

the reduction of ores, an alternating current electromagnet having a dual magnetic flux circuit and whose central core forms the ore charge to be reduced, in combination with a primary and a secondary coil placed concentrically with respect to said central core, and means for increasing the temperature of the lower end of said charge which consists in closing the terminals of the secondary coil through the ore charge.

4. An induction furnace comprising a vertical alternating current electromagnet whose central core forms the downward moving ore-charge of

the furnace; a secondary coil placed concentrically with the primary coil and with the central ore-charge of the electromagnet; means for passing two magnetic flux-circuits generated by the primary field coil, through the central ore-charge; in combination with means for raising the temperature of the ore-charge to the reducing point, by concentrations of the flux densities at each of said flux circuits at the lower end of said ore-charge, and means for vibrating the ore charge.

CLARENCE Q. PAYNE.
